Primary Examiner — Cynthia R Underwood

(74) *Attorney, Agent, or Firm* — Sheridan Ross P.C.

(57) **CLAIM**

The ornamental design for the cord management wrap, as shown and described.

DESCRIPTION

FIG. 1 is a perspective view of a cord management wrap; FIG. 2 is a front elevation view thereof; FIG. 3 is a rear elevation view thereof; FIG. 4 is a left elevation view thereof; FIG. 5 is a right elevation view thereof; FIG. 6 is a top plan view thereof; FIG. 7 is a bottom plan view thereof; FIG. 8 is a first perspective view of the cord management wrap in a wrapped state; and, FIG. 9 is a second perspective view of the cord management wrap in a wrapped state. The broken lines in the drawings illustrate portions of the cord management wrap which form no part of the claimed design.

1 Claim, 9 Drawing Sheets
